(57) **CLAIM**

The ornamental design for a base cabinet, as shown and described.

DESCRIPTION

FIG. 1 is a front perspective view of a base cabinet showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof;

FIG. 7 is a bottom plan view thereof;

FIG. 8 is a front perspective view showing an open configuration;

FIG. 9 is an enlarged rear perspective view showing the open configuration; and,

FIG. 10 is a front perspective view showing another open configuration.

The broken lines in the drawings illustrate portions of the article that form no part of the claimed design.

1 Claim, 10 Drawing Sheets
